UNITED STATES PATENT OFFICE.

MERRILL N. HUTCHINSON, OF NEW YORK, N. Y.

PASSENGER OR OTHER ELEVATOR.

SPECIFICATION forming part of Letters Patent No. 299,547, dated June 3, 1884.

Application filed November 1, 1883. (No model.)

To all whom it may concern:

Be it known that I, MERRILL N. HUTCHINSON, of the city, county, and State of New York, have invented certain Improvements 5 in Safety Apparatus for Passenger and other Elevators, of which the following is a specification.

This invention comprises certain novel combinations of parts for arresting the downward 10 movement of the car or cage of a passenger or other elevator in the event of the breaking of the hoisting rope or chain, such breaking of said rope or chain being caused to automatically bring into operation gripping-wedges 15 upon the opposite sides of a suitable post or standard in such manner that the gripping-wedges will retard and stop the aforesaid downward movement of the car or cage.

Figure 1 is a side view. Fig. 2 is a vertical 20 sectional view; Fig. 3, a plan view representing an apparatus embracing my said invention.

A is the car or cage, which may be of any usual or suitable construction. 25 B B are draft or hoisting ropes, which may be one or more in number, and actuated to raise or lower the car or cage in any ordinary or appropriate manner, and by means of any ordinary or suitable hoisting and lowering 30 mechanism.

C C are vertical posts, arranged at opposite sides of the car or cage A, as more fully represented at Figs. 2 and 3, the position of each post with reference to the adjacent side of the cage being shown in Fig. 1. Upon each of the two opposite sides of the cage are strong 35 guide-bars D, securely fixed to the cage upon opposite sides of the adjacent post C, as represented in Fig. 1. The said guide-bars D being placed in an inclined position, as represented in said Fig. 1, the spaces between their inner edges and the adjacent sides of the post C being narrowest at the top and widest at the bottom, the said post is substantially wedge-shaped.

E E are wedges corresponding in shape to the spaces between the post C and the guide-bars D, just hereinbefore described. These wedges are prevented from slipping outward 45 from their places by lugs or ears a, firmly fixed

to the guide-bars D, as shown in Fig. 1. In order that the said lugs or ears a may serve the further purpose of keeping the inner sides or surfaces of the wedges E out of immediate contact with the adjacent sides of the post C, 55 when said wedges are in their normal position, the said lugs a are turned upward to constitute (so to speak) hooks, behind which play upwardly-projecting studs b, the outer edges of the lugs or ears a being so shaped that as the 60 wedges descend the studs b, bearing against the outer edges of the lugs a, will draw the wedges slightly away from the post C, the arrangement being such, however, that when the wedges E are drawn upward no interference is offered to the crowding of the said wedges against the opposite sides of the post C. The two wedges at each side of the car or cage A are connected, by links c or other suitable device, with the outer arm, d, of a lever, 7c F, which is pivoted, as shown at e, to the top of the car or cage. The arm f of this lever F is formed with a head, g, which fits into cavities or recesses formed in opposite sides of a draft-block, G, which, by means of a rod, 75 H, or equivalent device, is connected with the lower extremity of the draft rope or chain B. The rod H passes upward through an opening in a horizontal yoke, I, secured upon the top of the cage A, and which limits the upward 80 movement of the block G, inasmuch as the lateral portions of the top of the latter form shoulders, which bear against the under side of the yoke I when the weight of the car or cage is sustained by the draft rope or chain 85 B. Springs are arranged in such manner as to tend to push downward upon the inner arm, f. These springs may be of any suitable kind or character, and arranged in any suitable manner. Thus, for example, springs i 90 may be arranged to bear between the yoke I and the head g, thereby tending to push downward the said heads, while other springs, k, may be arranged between the inner arms, f, of the levers F and the top proper of the car 95 or cage, thereby tending to draw downward the said arms f. In like manner springs m may be arranged between the outer arms of the levers f and the top of the car or cage, so as to push upward upon said outer arms to 100

In the normal use and operation of the car, when the same is suspended from the rope or chain B, the upward draft upon the inner arms, *f*, will release downward the wedges, so that the same shall not be in contact with the post C; but in the event of the breaking of the said rope or chain, the inner arms, *f*, of the levers moving downward, the wedges E will have their inner surfaces brought in contact with the sides of the post C, and, being forced snugly against the said sides by their wedge-like action by conjunction of the guide-bars, will retard the downward movement of the car or cage, and in a very brief interval of time will effectually stop the downward movement thereof. It is of course to be understood that while the springs applied to the levers F, as hereinbefore explained, materially assist the operation of the wedges, their use is therefore to be preferred, and while the stud *b* acts in conjunction with the upwardly-turned lug *a* to greatly facilitate the operation of the apparatus, yet it is quite feasible to secure the gripping action of the wedges E without the aid of these subordinate operations of my said invention. It is further to be observed that the posts C, instead of being placed with the flat sides of the car or cage A, may be placed at the corners thereof, the cross-section of the wedges E being modified to accommodate them to this changed position, the operation of the apparatus being substantially the same in the one case as the other. It will be observed that the heads *g*, being of metal and of considerable weight, serve to a certain extent the purpose of the springs, so that the apparatus will be capable of the use aforesaid even without the use of the springs.

What I claim as my invention is—

1. The combination of the posts C, car or cage A, having guide-bars D, arranged with wedge-shaped spaces between their inner edges and the adjacent sides of the post C, wedges E, placed in the said spaces upon opposite sides of the said posts C, and levers F, having their inner arms connected with the draft rope or chain B, whereby, in the event of the breaking of the said draft rope or chain, the wedges E may rise to grip the post C between them, all substantially as and for the purpose herein set forth.
2. The combination of the post C, the car or cage A, having guide-bars D, arranged with wedge-shaped spaces between their inner edges and the adjacent sides of the said post C, wedges E, placed in the said spaces, levers F, having their outer arms connected with said wedges and their inner arms connected with the draft rope or chain B, and springs *k*, arranged to force downward the inner arms of the levers F, when the latter are relieved from the upward strain exerted by the draft-rope in raising or lowering the car or cage A, all substantially as and for the purpose herein set forth.

3. The combination of the posts C, the car or cage A, having guide-bars D, with wedge-shaped spaces between their inner edges and the adjacent sides of the aforesaid posts C, links or connections *e*, levers F, head *g*, recessed block G, yoke H, and a draft rope or chain, B, connected with the said block G, all substantially as and for the purpose herein set forth.

MERRILL N. HUTCHINSON.
